Atkins

UNITED STATES PATENT OFFICE.

GENERAL M. DITTO, OF JOLIET, ILLINOIS.

WHIP-MANIPULATOR.

1,122,263.

Specification of Letters Patent. Patented Dec. 29, 1914.

Application filed March 5, 1914. Serial No. 822,643.

To all whom it may concern:

Be it known that I, GENERAL M. DITTO, a citizen of the United States, residing at Joliet, in the county of Will and State of Illinois, have invented a new and useful Improvement in Whip-Manipulators, of which the following is a specification.

This invention relates particularly to whip-manipulators adapted for use where the horses are so far removed from the driver as to render it impracticable to hold the whip directly in the hand.

The primary object of the invention is to provide an improved and simplified device which operates in an improved manner.

The improved device may be mounted in any suitable position, for instance, upon the evener of a pair of whiffle-trees; and the improved device is provided with a whip-holder which is pivotally mounted preferably on a swiveled head and actuated by a flexible shaft, which serves both to turn the swiveled head to the desired position to bring the whip over any selected horse, and serves also to actuate the whip-holder in a vertical plane to cause the whip to strike the horse.

The invention is illustrated in its preferred embodiment in the accompanying drawing, in which—

Figure 1 represents a broken elevational view showing my improved whip-manipulator mounted upon an evener, which is shown in section; Fig. 2 is a vertical section of the device, taken on the dotted line 2 of Fig. 3; Fig. 3 is a rear elevation of the device; and Fig. 4, a broken horizontal section taken as indicated at line 4 of Fig. 1.

In the illustration given, the device comprises a base or standard A equipped at its upper end with a fixedly-secured, curved, hollow swivel-member A'; B, a head or swivel-member mounted on the member A' and adapted to turn about a vertical axis 45 and a whip-holder connected by a pivot 1 to the upper end of the member B; and D, a flexible shaft connected with the whip-holder and extending through the hollow member A' which therefore acts as a guide for the flexible shaft. The flexible shaft D is equipped with an actuating rod D'. The standard A is shown as comprising a tubular member whose lower end is received in a base-plate 2. Through the base-plate 2 extends a headless bolt 3 which also pro-

jects into the lower end of the tubular standard and is secured by a lateral set-screw 4 which passes through the boss of the plate 2 and through the tubular member and engages the bolt 3. In the illustration given, the bolt 3 serves as a clevis pin connecting the evener 5 of the whiffle-trees to the clevis 6.

The base-plate 2 is provided with perforations 2*, by means of which the base-plate may be secured directly to the evener or any other suitable support by means of screws, when desired. In such case, the bolt 3 may be dispensed with.

The curved tubular member A' is provided with a shank 7 which is secured in the upper end of the standard A. The tubular member A' is of approximately elbow shape, having the upturned end 8 upon which the member B is swiveled, and having the rearwardly-turned lower end 9 through which the lower end of the flexible shaft is adapted to extend.

The member B has the tubular base-portion 10 adapted to turn on the upper end 8 of the member A', and is provided with a stop 11 adapted to engage shoulders 12 with which the part 8 is provided, so as to limit the swivel movement of the member B. The member B is further provided with arms or furcations 13 which extend upwardly from the tubular-member and support the pivot 1 upon which the whip-holder C is mounted. A coil-spring 14 serves to throw the whip-holder to the standing position shown in Figs. 2 and 3.

The whip-holder has a base-portion connected with a pivot 1 and has a laterally-opened socket 15 adapted to receive the butt of the whip 18 which is secured in place by a clamping-member 17. The whip-holder is provided with a forwardly-projecting arm 18 which is embraced by the furcations of a slotted member 19 which is rigidly secured to the upper end of the flexible shaft 100 D and connected with the arm 18 by a pivot 20.

The lower end of the flexible shaft is equipped with a fixedly-secured socket 21 which receives the adjacent end of the rod 105 D', the parts being secured together by a cotter-pin 22 which bears against the end 9 of the tubular member A' when the whip-holder is thrown to the vertical position by the spring 14. The rod D' may be of any 110

suitable length and is equipped at its rear end with a handle 23, which should be located within convenient reach of the driver.

In the use of the device, the driver turns 5 the rod D' in such direction as to cause the swiveled-member B to turn to the proper position to bring the whip over any selected horse, and the driver then pulls the rod, thereby swinging the whip downwardly so 10 that it will strike the horse. When the handle 23 is released, the spring 14 turns the whip to the standing position. It will be noted from Fig. 2 that by reason of the lateral projection of the arm 18 from the 15 base-portion of the whip-holder, the member B may be turned freely upon its vertical axis through the medium of the flexible shaft; also, that the whip-holder may be actuated freely, regardless of the position 20 of the member B, the flexible shaft slipping freely through the member A' when the rod D' is pulled.

The foregoing detailed description has been given for clearness of understanding 25 only, and no unnecessary limitation should be understood therefrom, but the appended claims should be construed as broadly as permissible in view of the prior art.

What I regard as new and desire to secure 30 by Letters Patent is—

1. In a device of the character set forth, the combination of a suitable support equipped with a swivel-member, a swivel-member mounted thereon, a whip-holder 35 mounted on said second-named swivel-member, a curved flexible shaft adapted to turn the second-named swivel-member on its axis and also to actuate the whip-holder, and a guide for the curved portion of the shaft.
2. In a device of the character set forth, the combination of a support equipped with a tubular swivel-member, a swivel-member mounted thereon, a whip-holder movably connected with said second-named swivel- 40 member, a flexible shaft connected with said whip-holder extending through said tubu- 45

lar swivel-member and adapted to turn the second-named swivel-member on its axis and also to actuate the whip-holder, and a handle connected with said flexible shaft.

3. In a device of the character set forth, the combination of a standard having its upper end equipped with a curved tubular swivel-member, a swivel-member mounted thereon, a whip-holder pivotally connected 55 with said second swivel-member and equipped with a forwardly-projecting arm, a flexible shaft extending through said tubular swivel-member and having its upper end connected with said arm, and an actuating 60 rod connected with said flexible shaft.

4. In a device of the character set forth, the combination of a support equipped at its upper end with a swivel-member, a swivel-member mounted thereon, a whip-holder pivotally mounted on said second-named swivel-member, a spring serving to move said whip-holder to standing position, a flexible shaft having sliding engagement 65 with said first-named swivel-member and adapted to turn the second-named swivel-member on its axis and also to actuate the whip-holder, and an actuating rod connected with said flexible shaft.

5. In a device of the character set forth, the combination of a supporting-member 70 equipped with a tubular swivel-member, a swivel-member mounted thereon, stops serving to limit the rotation of said second-named swivel-member, a spring-held whip-holder pivotally connected with said second-named swivel-member, a flexible-shaft extending through said first-named swivel-member and connected with said whip-holder and adapted to turn the second-named swivel-member on its axis and also 75 to actuate the whip-holder, and an actuating-rod connected with said flexible shaft.

GENERAL M. DITTO.

In presence of—

O. C. AVISUS,
F. A. FLORELL.
